TIMER

Filed Jan. 23, 1922

UNITED STATES PATENT OFFICE.

BURTON U. HILLS, OF CHICAGO, ILLINOIS.

TIMER.

Application filed January 23, 1922. Serial No. 531,177.

My invention belongs to that general class of devices known as timers or timing devices for internal combustion engines. As is well known, timing devices or timers as they are generally known, are adapted for successively closing an electrical circuit to the several sparking devices from a common source and thereby igniting the charges in the cylinders to operate the engine.

10 My invention has among its objects the production of a device of the kind described that is simple, convenient, compact, durable, efficient, reliable and satisfactory for use wherever found applicable.

15 Another object of my invention is to provide an insulating means for the interior of the casing, so arranged that it will lay close against the casing and will not be drawn away by the expansion or contraction of the 20 insulating material or otherwise damaging the insulation.

Another object of my invention is to provide lubricating means whereby the rotor periphery may be lubricated while it is in 25 motion so as to prevent excessive wear between the rotor and the cooperating contact members.

Many other objects and advantages of the 30 construction herein shown and described will be obvious to those skilled in the art from the disclosure herein given.

To this end my invention consists in the novel construction, arrangement, and combination of parts herein shown and described, and more particularly pointed out in 35 the claims.

In the drawings, wherein like reference characters indicate like or corresponding parts,

40 Fig. 1 is a side elevation of my improved device mounted for use;

Fig. 2 is a view in elevation of my improved device viewed from the rear thereof;

45 Fig. 3 is a cross-sectional view taken substantially on the line 3—3 of Fig. 2;

Fig. 4 is a cross-sectional view taken substantially on the line 4—4 of Fig. 3; and

50 Fig. 5 is a cross-sectional view taken substantially on the line 5—5 of Fig. 4, and

Fig. 6 is a face view of the rotor and contact.

Referring to the drawings, in which the preferred embodiment of my invention is shown, 1 represents the timer driving shaft 55 driven in the usual or any preferred manner having mounted thereon a rotor 2, formed of

fiber or other non-conducting material, preferably made as has been described in my copending application, Serial No. 444,174, filed February 11, 1921. The rotor is preferably circular in form and is mounted upon a sleeve 3 formed of brass or any other suitable electrical conducting material which is in turn secured to the shaft 1 in any preferred manner so as to be driven thereby. A 60 cap or cover 4, enclosing the projecting end of the sleeve 3, is preferably of a length to engage with the face of the body of the rotor, the extreme edge of the cap being preferably flanged so as to lie against said 65 rotor. The cap 4 is mounted in position on the shaft and against the rotor, maintaining the rotor firmly in place by means of a suitable nut 5 or other means mounted on the 70 extreme end of the shaft. 75

In the form of device shown, the rotor 2 is circular in form as previously mentioned, the outer periphery having a face of non-conducting material except at a point where the contact member 6 is positioned, this contact member consisting preferably of a sheet-metal plate shaped to the form shown in the drawings and firmly secured to the rotor in any suitable manner. The periphery 80 of the member 6 is flush with the periphery 85 of the rotor, being made so by any suitable process to secure a smooth and true face, as by grinding or the like. The peripheral portion of the member 6 is so formed that its extremities are of substantially the same 90 width as the thickness of the valve 2; the side portions of the member 6 being cut away slightly at these points to avoid any possible tendency to strike against the cooperating 95 parts. The contact member on the rotor is 95 arranged to cooperate with the desired number of contact points or members 20, as the rotor is driven. As shown, I provide a casing 19 of the desired size, shape and material, preferably circular in cross-section 100 and which normally encloses the rotor and prevents the admission of foreign matter such as dust, grit, dirt, moisture or grease, etc., thereto, the same being detachably maintained in place in the construction shown, by 105 its engagement with the body of the engine or other supports carrying the shaft 1, and the member 26 mounted on an adjacent part 27. Member 26 is provided with a protruding part arranged to engage in a depression 110 at the end of the cover of the casing, it being understood, however, that the particular

- construction and the method of supporting the same may be varied as desired. The construction illustrated, however, permits the casing which carries the contact members 20 to be partially rotated or adjusted, there being a bracket 22 in the particular device shown carried by the casing and adapted to cooperate with a shifting or adjusting rod 23 for the adjusting of the casing.
- 10 Arranged on the casing are the desired number of binding posts comprising screws 7 and 8 held in place by nuts 9, or their equivalents, there being insulating washers 11 between the casing and the screws. Adapted 15 to cooperate with the binding screws 7 and 8, respectively, are binding nuts 7' and 12, for clamping or otherwise securing the electrical conductor at the binding posts. The number of binding posts depends upon the 20 particular use for which the device is intended for instance on an internal combustion engine, I provide one binding post for each spark plug or other igniting device, the contacts on the spark plugs being connected 25 therewith by suitable conducting wires or the equivalent in the usual manner (not shown). The binding screws extend within the casing and each are electrically connected with spring members 21 carrying the contacts or brush members 20. The springs 30 preferably extend in the direction of the rotation of the rotor, as shown by the arrow in Fig. 2, and serves the double purpose of maintaining the contact members 20 in engagement with the surface of the contact 35 part 6 and with the periphery of the rotor, and at the same time as electrical conductors connecting the members 20 with the binding posts and securing them in place.
- 40 I prefer to provide strips 28 of non-conducting material around the interior of the shell to further insulate the electrical contact members from the casing. The strips extend circumferentially of the casing, being secured thereto at one end in the construction illustrated by the binding screws and the nuts 9, the free ends of adjacent strips overlying one another, as at 29, so that as the insulation strips or the casing expand or contract, the overlapping ends of the insulating material may slide upon each other to compensate for such expansion or contraction, and not buckle up or fall away from the casing.
- 45 55 There will be very little friction between the contact parts 20 and 6 to cause wear therebetween when the rotor is constructed as described in my application referred to, but in order to minimize even this small amount of wear, I have provided lubricating means whereby oil or other suitable lubricating fluid may be supplied to the periphery of the rotor while it is in motion. As shown, the binding screw 8, projecting 60 65 into the interior of the casing, is axially

bored as at 10, as shown in Fig. 4, to form an oil duct therethrough. The binding nut 12 has a hollow cylindrical portion 13 extending axially thereof, said cylindrical portion being adapted to receive a cylindrical 70 casing constituting an oil-receiving chamber 14, said oil chamber casing being secured therein in any suitable manner as desired. Preferably it is a drive fit, or held in by friction. The outer edge of said oil chamber casing 14 is inwardly flanged as at 75 15 and has an oil hole or inlet 15' in said flanged end wall. Slidably carried in said chamber is a valve 16 having one or more guide arms 17 projecting inwardly and maintaining a resilient coiled spring 18 therebetween, said spring serving to normally maintain the inlet opening 15' closed. In order to lubricate the rotor, it is only necessary that the valve 16 of the oil chamber be pressed inwardly and the oil applied thereto, whereupon it will flow through the duct 10 and onto the periphery of said rotor. It will be noted that the valved oil chamber is unitary with the binding post nut, and is extremely compact and convenient to use. To prevent leakage of the oil down the outside of the screw and along the threads, I prefer to place a washer 14', as shown, the same being of felt or any other suitable material. It will be noted that the inner or head end of the binding post substantially constitutes a spout from which the oil will drop without running over the side of the head.

100 The operation of the device may be briefly described as follows: Assuming that the timer is applied substantially as shown, the binding posts being connected with the ignition apparatus and the shaft 1 grounded or connected with the source of electrical energy, then as the rotor 2 is driven by the shaft, the contact member 6 at its peripheral portion successively contacts with the several contact members 20, so that the several 105 circuits through the several binding posts are successively opened and closed. If the casing is partially rotated or adjusted, then obviously, the time of contact between the members 6 and 20 is varied, being either retarded or advanced depending upon the adjustment made. It will be noted that with this construction the members 20 are at all 110 times maintained in perfect contact with the face of the rotating rotor and that as the springs 21 of the contact members 20 are substantially tangential to the finished edge or periphery of the rotor, the casing may be shifted in either direction without danger of the contacts 20 engaging or ruffling up the face of the rotor or of the contact member 6'. Furthermore, this construction also requires less pressure to be put on the contact 115 20 in order to maintain it in place and there is consequently less wear on the parts.

As has been more fully described in my copending application hereinbefore mentioned, the rotor is preferably impregnated so as to be substantially water-proof and so 5 that the same does not take up oils or grease irregularly about the surface, as would be the case where a porous body was employed.

Having thus described my invention, it is obvious that various immaterial modifications may be made in the same without departing from the spirit of my invention; hence I do not wish to be understood as limiting myself to the exact form, construction, arrangement and combination of parts here- 15 in shown and described, or uses mentioned.

What I claim as new and desire to secure by Letters Patent is:

1. In an ignition timer, a casing, a rotor within said casing and made of insulating material having a metallic member in the periphery thereof adapted to be intermittently engaged by cooperating electrical contacts carried by said casing, one of said contact members carried by said casing having means for lubricating the periphery of said rotor while said rotor is in motion.

2. In an ignition timer, a casing, a rotor of insulating material having a metallic member on a portion of the periphery thereof, binding posts carried by said casing and insulated therefrom, electrical contact members carried by said binding posts and adapted to intermittently engage said metallic member of the rotor, one of said binding posts having an oil duct therethrough, and means for lubricating said rotor through said duct.

3. In an ignition timer, a casing, a rotor of insulating material having a metallic member on a portion of the periphery thereof, binding posts carried by said casing and insulated therefrom, electrical contact members carried by said binding posts and adapted to intermittently engage said metallic member of the rotor, one of said binding posts having an oil duct therethrough, means for lubricating said rotor through said duct, and means for yieldably maintaining said oil duct normally closed at the exterior.

4. In an ignition timer, a casing having binding posts thereon and insulated therefrom, a rotor adapted to rotate within said casing, a metallic member on the periphery of said rotor, electrical contact members carried by said binding posts and adapted to cooperate with said metallic member of the rotor, and means for lubricating said rotor while it is in motion, said means comprising an oil chamber carried by one of said binding posts, said last mentioned binding post having a duct therethrough leading from said oil chamber to the interior of the casing.

5. In an ignition timer, a casing having binding posts thereon and insulated there-

from, a rotor adapted to rotate within said casing, a metallic member on the periphery of said rotor, electrical contact members carried by said binding posts and adapted to cooperate with said metallic member of the rotor, and means for lubricating said rotor while it is in motion, said means comprising an oil chamber carried by one of said binding posts, said last mentioned binding post having a duct therethrough leading from said oil chamber to the interior of the casing, and provided with substantially a spout at the inner end thereof.

6. In an ignition timer, a casing, binding posts thereon and insulated therefrom, said binding posts comprising a binding screw secured to the casing, one of said binding screws having a duct therethrough, and a binding nut engageable on said screw and having an oil-receiving chamber thereon adapted to communicate with said duct, whereby lubricant may flow through said chamber and duct to the interior of said casing.

7. In an ignition timer, a casing having binding posts carried thereon, and strips of insulating material arranged within said casing circumferentially thereof, said strips of insulating material having their adjacent ends overlapping so as to automatically compensate for expansion or contraction of the parts.

8. In an ignition timer, a casing having binding posts thereon and insulated therethrough, and insulating strips circumferentially arranged on the inner wall of said casing, said strips each having one end secured to said casing and their adjacent ends overlapping so as to compensate for the expansion or contraction of the parts.

9. In an ignition timer, a casing, a rotor of insulating material having a metallic member on a portion of the periphery thereof, binding posts carried by said casing, and electrical contact members connected to said binding posts and adapted to engage said rotor, one of said binding posts having an oil duct therethrough.

10. An electrical binding post comprising a tubular screw-threaded shank having a head at one end, a nut threaded upon said shank, a second nut threaded upon said shank and adapted to cooperate with the first-mentioned nut to connect an electrical terminal to the shank, said second nut having a tubular extension communicating with the passage through said tubular shank whereby a lubricant may be introduced into said shank, and valve means disposed in said tubular extension.

In testimony whereof, I have hereunto signed my name.

BURTON U. HILLS.
